Primary Examiner — L. Martinez(74) *Attorney, Agent, or Firm* — Alan D. Kamrath; Karin L. Williams; Mayer & Williams PC(57) **CLAIM**

The ornamental design for an extrusion, as shown.

DESCRIPTION

FIG. 1 is a perspective view of an extrusion showing our new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The extrusion is shown with symbolic break lines along its length. Any portions of the extrusion between the break lines form no part of the claimed design.
